INVENTOR
BY *Morris S. Finkelstein*
Frank M. Miller ATTORNEY

UNITED STATES PATENT OFFICE.

MORRIS S. FINKELSTEIN, OF NEW YORK, N. Y.

LOCK.

Application filed February 28, 1922. Serial No. 539,867.

To all whom it may concern:

Be it known that MORRIS S. FINKELSTEIN, a citizen of the United States, and a resident of New York city, in the county of 5 New York and State of New York, has invented certain new and useful Improvements in Locks, of which the following is a specification.

My invention relates to locks and especially to locks for use with doors mounted on hinges and opening outward.

The object of my invention is to provide a lock and bolt construction adapted to be operated by a key and an extra brace-bolt 15 which is carried into locked position by the primary bolt, and thus provide a lock of exceptional strength.

Referring to the drawings which form a part of this specification,

20 Figure 1 is a front elevational view of my lock construction shown partly in section and in locked position.

Figure 2 is a similar view showing the lock in unlocked position.

25 Figure 3 is a side view of the construction illustrated in Figures 1 and 2.

Figure 4 is a side view illustrating a modified form.

A, indicates a portion of a door which 30 opens outwardly, the view being taken from the inside of the door on which side the lock is located. B, indicates the lock frame and D indicates the door frame. C, indicates the brace-frame which is made of strong metal 35 and is mounted on the door frame as illustrated, said frame comprising an opening C' to receive the end of the main bolt and a plate portion C² extending at a right angle thereto and preferably formed integral 40 therewith.

The lock-frame B is provided with a suitable slot in which is located the main bolt E, which when in locked position extends into the usual recess formed in the door 45 frame D.

The main bolt E is provided with a transverse slot E' in which the upper end of the brace-bolt F is adapted to fit and be carried into a recess G formed in the lock-frame, by the main bolt E in its locking movement. The lower end of the brace-bolt is located in a rectangular shaped tube H formed integral with the plate portion C in which it fits in sliding relation. The lock

I is provided with a lever I' which in its 55 rotational movement enters the slot J formed in the main bolt to move the bolt. In Figure 4 a modified form is shown in which the brace-bolt extends through an opening K formed in the plate C' instead 60 of the tube construction H. It will be seen that if the main bolt should be sawed off on the line X—X of Figure 1, the brace bolt still secures the door.

The operation is as follows: 65

Assuming the main bolt to be in unlocked position and the door closed: The brace-bolt is positioned as shown in Figure 2 and when the lock I is operated by a key the latch I' enters the slot J and forces the main bolt 70 into locked position as shown in Figure 1, the bolt E extending into the casing D and the brace-bolt F being carried into the recess G and under the overhanging plate G' of the lock-frame thus securing the door 75 with two bolts both of which are controlled by a single key.

Having thus described my invention I claim as new:

1. A lock comprising a frame and a plate 80 portion, said frame having a slot and recess therein, a main bolt carried by said frame, a brace bolt slidably mounted on said plate portion adapted to cooperate with said slot and recess and controlled by said main bolt. 85

2. A lock comprising a frame and a plate portion in said frame having a vertical slot and a recess adjacent thereto, a main bolt carried by said frame and adapted to be operated by a key, a right angle brace bolt, 90 one arm of which is slidably mounted on said plate portion, the other arm of said bolt engaging said main bolt and cooperating with said slot and recess.

3. A lock comprising a frame and a plate 95 portion, said frame having a vertical slot and a recess formed adjacent thereto, and a main bolt slidably mounted on said frame, a brace-bolt carried by said plate portion and adapted to enter said slot and recess 100 and operated by said main bolt.

Signed at New York, in the county of New York and State of New York, this 15th day of February, A. D. 1922.

MORRIS S. FINKELSTEIN.

Witness:

FRANK M. ASHLEY.
